UNITED STATES PATENT OFFICE.

WILLIAM TWEEDDALE, OF BROOKLYN, ASSIGNOR TO THE NORTH AMERICAN IRON WORKS, OF NEW YORK, N. Y.

DESIGN FOR A GATE.

SPECIFICATION forming part of Design No. 20,730, dated May 19, 1891.

Application filed March 13, 1891. Serial No. 384,956. Term of patent 14 years.

To all whom it may concern:

Be it known that I, WILLIAM TWEEDDALE, a citizen of the United States, residing at Brooklyn, in the county of Kings and State 5 of New York, have invented and produced a new and original Design for a Gate, of which the following is a specification, reference being had to the accompanying drawing, forming part thereof.

10 I have illustrated my gate in the drawing by an elevation.

The leading feature of my design is a circular central ornamental open-work figure between side and bottom ornamental bars and 15 a top scroll-plate with intermediate arabesque leaf scroll ornaments.

a a' are the molded side bars, each having a row of raised knob ornaments.

b is the base-bar, and there are block ornaments b' where the side and base bars meet.

c is the center rosette and ring ornament, and disposed radially therefrom are the alternating scroll and leaf ornaments d e.

f g are concentric rings, and between said 25 rings are disposed the raised quarterfoil ornaments h and the bar and curve ornaments i.

Disposed outside of the ring g are bar ornaments k, and in the upper part of the gate is a curved scroll-plate l. Around the ring g 30 are the arabesque leaf scrolls m, as shown. n

is a scroll ornament below the bar b, and acorn-knobs o at the lower ends of the bars a a' and leaf, ball and acorn finials s s' at the upper ends of the bars a a'. Above the plate l is a standard r and representation of a basket of fruit r', and at each side thereof are arabesque leaf scrolls t, as shown. 35

What I claim is--

1. The design of the ornamental shape and configuration of the gate, substantially as 40 shown and set forth.

2. In the design for a gate herein shown and described, the design of the frame comprising the molded bars a, a', and b, the ornaments o b' and s s', the scroll-plate l, the 45 standard r, and fruit-basket r', and the arabesque leaf scrolls t, as set forth.

3. In the design for a gate herein shown and described, the design of the central portion comprising the arabesque leaf scrolls m, 50 ornaments k, the rings f g, the quarterfoil ornaments h, and the ornaments c, d, e, and i, as set forth.

Signed by me this 9th day of March, A. D. 1891.

WILLIAM TWEEDDALE.
